UNITED STATES PATENT OFFICE.

ALBERT C. BECKEN, OF CHICAGO, ILLINOIS.

BRACELET WATCH-HOLDER.

1,093,758.

Specification of Letters Patent. Patented Apr. 21, 1914.

Application filed June 23, 1913. Serial No. 775,338.

To all whom it may concern:

Be it known that I, ALBERT C. BECKEN, a citizen of the United States of America, and a resident of Chicago, county of Cook, and 5 State of Illinois, have invented certain new and useful Improvements in Bracelet Watch-Holders, of which the following is a specification.

My invention relates to bracelet watch 10 holders and has for its object the construction of a holder for watches, lockets, etc., which may be conveniently secured to the wrist by the use of one hand only.

In the accompanying drawings Figure 1 15 is an elevation of a watch and holder in its closed position as it is upon the wrist of a wearer; Fig. 2 is a similar elevation with the locking part of the bracelet in unlocked position; Fig. 3 is a similar elevation with the 20 bracelet open; and Figs. 4 and 5 are enlarged plan and elevation, respectively, of the locking device.

Soldered or brazed to one side of the watch W is a metallic spring A, shaped to 25 the contour of the lower half of the wrist, and terminating in a tongue B located between two hooks C. The tongue and hooks are integral with the part A, and hinged in these parts is a locking lever or clasp D.

30 These parts are similar in construction and operation to the clasps or buckles on ordinary "arctics" and do not need detail description. As is well known in such clasps, the part D may be moved by hand from the position shown in Fig. 1 to the position shown in Fig. 2, and vice versa, and the part D will be held in either position by the spring action of the tongue B. Similarly secured to the other side of the watch W is a

40 short piece E, and hinged at F to this piece is a curved spring part G. The hinge at F is the same as the hinge connection between A and D, and permits the part G to be moved from the position shown in Fig. 1 to the position shown in Fig. 3. The joint F also acts to hold the parts G in either of these 45 positions in the same way that the connection between A and D acts to hold the part D in either of the positions shown. For

50 convenience, a hinge of the character of that at F will be called a "snap joint," and the part D with its associated connections will be called a "locking device."

Connected by a plain hinge H to the part 55 G, is a link J having slots K through which

the free end of the clasp D may pass in locking or unlocking the bracelet.

The several parts so far described are so shaped that when the bracelet is closed, as shown in Fig. 1, the inclosed space corresponds closely to the shape of the wrist, and when the bracelet is open, as shown in Fig. 3, it may be readily slipped off the wrist.

In applying the holder, it is opened as shown in Fig. 3, and slipped over the wrist, 65 and the part G is closed down as shown in Fig. 2. In this condition the snap joint F holds the bracelet in position on the wrist with a moderate force sufficient to enable the operator to connect the parts J and D without danger of displacing the bracelet during 70 such connecting operation.

What I claim is:—

1. In a bracelet holder, a watch, a spring 75 secured to one side of the watch and shaped to correspond in form to a portion of the circumference of the wrist, a second spring secured to the other side of the watch and shaped to correspond in form to the opposite side of the wrist, a snap joint in the connection between the second spring and the watch, and a locking device for holding the second spring for displacement on its snap joint.

2. In a bracelet holder, a watch, a spring 85 secured to one side of the watch and shaped to conform substantially to the form of the wearer, a second spring secured to the other side of the watch and shaped to correspond to the other side of the wrist, a hinge in the 90 form of a snap joint by which one side of the bracelet may be opened, and locking devices for securing the two sides of the bracelet together when closed.

3. In a watch holder, a watch, a spring 95 secured to one side of the watch and shaped to correspond to one side of the wrist of the wearer, a second spring secured to the other side of the watch and shaped to correspond to the other side of the wrist, and adjustable locking devices for securing the free ends of the springs together on the side of the wrist opposite the watch.

Signed at Chicago, Illinois, this 20th day of June 1913.

ALBERT C. BECKEN.
